DESIGN FOR A METAL CHAIR OR SIMILAR ARTICLE

Irving Salomon, Chicago, Ill.

Application June 5, 1939, Serial No. 85,352

Term of patent 7 years

To all whom it may concern:

Be it known that I, Irving Salomon, a citizen of the United States, residing at Chicago, in the county of Cook and State of Illinois, have invented a new, original, and ornamental Design for a Metal Chair or Similar Article of which the following is a specification, reference being made to the accompanying drawing, forming a part thereof in which

Fig. 1 is a perspective view of a metal chair or similar article embodying my new design;

Fig. 2 is a side elevational view thereof;
Fig. 3 is a front elevational view of the same;
and

Fig. 4 is a top plan view thereof.

I claim:

The ornamental design for a metal chair or similar article, as shown.

IRVING SALOMON.
